UNITED STATES PATENT OFFICE.

DANA ESTES, OF BROOKLINE, MASSACHUSETTS.

FIRE-EXTINGUISHER.

1,274,699.

Specification of Letters Patent.

Patented Aug. 6, 1918.

Application filed March 12, 1915. Serial No. 13,848.

To all whom it may concern:

Be it known that I, DANA ESTES, a citizen of the United States, and resident of Brookline, in the county of Norfolk and State of Massachusetts, have invented certain new and useful Improvements in Fire-Extinguishers, of which the following is a specification.

This invention relates to hand fire extinguishers of the type which comprises a container for liquid and manually operable means for forcing the liquid from the container.

It is desirable to keep the container tightly sealed when it is not in use, to prevent loss of liquid through evaporation; and one of the objects of the present invention is to provide sealing means for this purpose. The container is in the form of a cylinder, and a piston is arranged in the cylinder to act upon the liquid for the purpose of discharging the latter. The piston-operating means and the sealing means hereinbefore mentioned are physically connected in such relation that the movement imparted to the piston-operating means effects the unsealing of the container. The user is thus relieved of performing a preliminary operation for unsealing. It may be remarked at this time that the container is sealed and unsealed at both ends. The outlet is sealed automatically upon the completion of each forward impulse imparted to the piston.

It is desirable to prevent leakage past the piston, and for this reason I have provided piston-operating means which is arranged wholly behind the piston, no part of such means extending through the piston. This leaves the piston without any opening through it, with the exception of a stuffing box which coacts with a smooth cylindric rod which is provided to seal the outlet. The said rod is of relatively small diameter, and the fact that it is cylindric and smooth enables the stuffing box to maintain a substantially leak-proof connection between it and the piston.

Of the accompanying drawings, which illustrate one form in which the invention may be embodied:

Figure 1 represents a side elevation of a fire extinguisher, the cylinder thereof being partly in section. In this figure the piston is a short distance ahead of its extreme rear

position, and the seal at the rear end of the cylinder is shown as having been unsealed to permit the entrance of air behind the piston.

Fig. 2 represents a view similar to Fig. 1, showing the piston advanced nearly to its extreme forward position.

Fig. 3 is a longitudinal section on a larger scale, intermediate portions of the device being broken out and the cylinder shortened to economize space. The forward and rear seals are both in sealing position in this figure, as when the device is fully charged and the piston at its extreme rear position.

Fig. 4 represents a longitudinal section of the discharge end of the container, and corresponds to the left-hand section of Fig. 3. In Fig. 4 the valve which seals the outlet is retracted from its seat, as when the piston is in the act of discharging liquid through the outlet.

The same reference characters indicate the same parts wherever they occur.

The container comprises a cylindric tube 10, a head 11 at the forward end, and a head 12 at the rear end. A discharge nozzle 13 is screwed into the head 11 and is made tight by a washer 14. The nozzle has an outlet passage whose diameter is relatively small at the forward end, as indicated at 15, and relatively large at the rear end, as indicated at 16. It also has a valve seat 17 connecting the portions of different diameter. A valve 18 is arranged to coact with the seat 17, said valve being formed upon the forward end of a cylindric rod 19. The diameter of the rod is materially less than the diameter of the larger portion 16 of the outlet passage, to provide sufficient space through which the liquid may pass, without entirely withdrawing the rod from said passage.

A piston 20 is provided to discharge liquid from the container. The piston is operated by means which includes a shaft 21. This shaft extends through the rear head 12 and is provided with a handle 22. The head 12 is formed with a boss 23 to provide a stuffing box for the shaft 21. The boss is formed with an annular reentrant flange 24 which surrounds the shaft and which is bored slightly larger than the shaft in order to admit air into the cylinder as the piston advances. The gland of the stuffing box is indicated at 25, and packing material is in-

dicated at 26. The gland is movable axially, and when it is in the position shown by Fig. 3, the packing material is compressed between the gland 25 and the forward end 5 of the reentrant flange 24. The gland has an annular extension 27 which surrounds and engages the flange 24. The shaft-receiving opening in the gland 25 is slightly larger in diameter than the shaft, to enable 10 air to enter the cylinder as the piston advances, the packing material 26 being relieved of compressive stress when the piston is advancing, as will be understood after further explanation.

15 The shaft 21 and valve rod 19 are rigidly connected with each other, such connection being effected in the present instance by screwing the rear end of the rod into the forward end of the shaft, as indicated at 28 in 20 Fig. 3. A cylindric collar 29 is threaded upon the rod 19 and set tightly against the forward end of the shaft, being in effect a binding nut for tightening the connection between the rod and shaft. This collar has 25 another function which is hereinafter explained. The distance from the valve 18 to the handle 22 is greater than the distance from the valve seat 17 to the rear end of the boss 23, this difference insuring seating of 30 the valve rather than seating the handle against the boss.

The piston comprises a disk 30 in addition to the element indicated at 20. The member 30 is made of metal, and the member 35 20 is preferably made of some soft material, such as leather, and impregnated or otherwise prepared with some substance which will preserve it against the chemical action of the liquid used in the device. The 40 disk 30 is provided with a stuffing box which coacts with the rod 19. This stuffing box includes an annular flange 31 which is internally threaded to receive a threaded gland 32. The packing material is indicated at 33. 45 The flange 31 is externally threaded to receive a nut 34, said nut being provided to secure a washer 35 against the forward side of the piston member 20.

The handle 22 is intended to be rotated 50 for the purpose of moving the piston longitudinally, and I will now describe the connections between the shaft 21 and the piston. The shaft has a collar 36 in front of the gland 25, said collar and gland being arranged to coact with each other as shown by 55 Fig. 1 and as hereinafter explained. The shaft has an external screw-thread 37 in front of the collar, said screw-thread running to the collar 29 at the forward end of 60 the shaft. The screw portion 37 and piston member 30 are connected by a plurality of telescoping sleeves 38, 39 and 40, the forward end of the latter being fastened to a flange 41 formed upon the rear side of the 65 piston member 30. The member 40 may be

fastened to the flange 41 in any suitable manner. The member 40 as shown has a "drive" fit over the flange. Sleeve 38 has at its rear end a nut portion 38' which coacts with the thread 37. Sleeve 38 has an external screw-thread 42, and sleeve 39 has at its rear end a nut portion 39' which coacts with the said thread 42. In like manner sleeve 39 has an external screw-thread 43, and sleeve 40 has at its rear end a nut portion 40' which coacts 70 with the said thread 43. The collar 29 coacts with nut portion 38' to limit the forward movement of the sleeve. The forward movement of sleeve 39 relatively to sleeve 38 is limited by an external flange 44 formed 75 upon the forward end of sleeve 38 and arranged to coact with nut portion 39'. In like manner forward movement of sleeve 40 relatively to sleeve 39 is limited by an external flange 45 formed upon the forward 80 end of sleeve 39 and arranged to coact with nut portion 40'.

In practice, when the handle 22 is rotated to expel liquid from the cylinder, the speed of movement of the piston will be limited by 90 the capacity of the outlet 15; and since liquid substance is not compressible, the rotative movement of the handle would be limited unless some provision were made for storing energy due to excess movement of 95 the handle. I have therefore provided a spring for storing the energy which causes such excess movement of the handle, said spring, in reacting, causing a continuing movement of the piston after rotative movement of the handle has ceased. The spring 100 for this purpose is indicated at 50. This spring is helical in form and surrounds the several telescoping sleeves. The rear end of the spring is seated against the rear head 12, and the forward end of the spring is seated 105 against a flange 51 formed upon a sleeve 52. The rear end of sleeve 52 is fastened to a flange 53 formed upon the member which has the gland 25 and flange 27. The spring 110 50 is always under compression, but its degree of compression will be increased whenever the sleeve 52 is moved toward the rear 115 of the cylinder. The rotative movement of the handle results primarily in advancing the piston through the medium of the screw sleeves; but if such rotative movement exceeds the rate at which the piston may advance, the screw sleeves react upon the screw shaft 21, moving the latter to the rear while 120 the piston is moving forward. As the collar 36 bears against the gland 25, as shown by Fig. 1, (excepting when the piston is fully retracted) the reactionary movement of the screw shaft 21 results in compressing the 125 spring 50, the liquid in front of the piston at such time acting as the abutment against which the screw members act to compress the spring. The spring, of course, reacts as soon as rotative movement of the handle 130

ceases, thus prolonging the advancing movement of the piston and ultimately causing the valve 18 to engage its seat.

In practice, the cylinder will be filled 5 through the forward end, and for this purpose the nozzle 13 will be unscrewed and removed. The forward head 11 is provided with a cup-shaped flange 54 to facilitate the charging operation. Before pouring the 10 liquid into the cylinder, the piston will be retracted as far as it will go, by turning the handle 22 in the direction opposite that required to discharge liquid. When the handle 22 is thus turned in the reverse direction it 15 draws the several screw sleeves 38, 39 and 40 to the rear, causing all said sleeves to abut against the flange 53. When all the sleeves have thus been screwed against the said flange, further reverse rotation of shaft 21 20 will move the several screw sleeves and the member 25, 27, 53 bodily to the rear. The operation of retracting the piston preparatory to recharging the device will preferably be performed before the nozzle 13 is removed, and the retractive movement imparted to the member 25, 27, 53 will compress the spring 50. When the nozzle 13 is 25 removed, it releases the rod 19 and shaft 21 so that the handle 22 may be moved into engagement with boss 23 by the expansive action of spring 50. Incidentally this movement relieves the compression of packing material 26, provided said packing material has been compressed before the removal of 30 the nozzle.

The space in front of the piston cannot be completely filled with liquid, because the head 11 has a reentrant nipple 55 through which the liquid must be poured. This insures an air space equal in area to the space 40 at the left of dotted line 56 in Fig. 3, the purpose of which is hereinafter explained.

Assuming now that the cylinder is charged with liquid and that the nozzle 13 is screwed 45 in to the position shown, the valve seat 17 will engage the valve 18 before the nozzle has been tightened relatively to the head 11, and the rod 19 and shaft 21 will be moved slightly to the rear by the nozzle. When the 50 nozzle has been made tight in the head 11 the device is tightly sealed at both ends, the two seals reacting against each other through the elements which connect them, and the pressure of the valve 18 against the 55 seat 17 being augmented by the expansive action of spring 50.

When using the device, the user has only to turn the handle 22 to the right (the several screw-threads being left) to move the 60 piston forward. When the handle is so turned, it causes first a slight advance of the piston, the air in front of the piston, hereinbefore mentioned, being compressible to permit such advance. At the same time, the 65 member 25, 27, 53 will have moved with the

piston in response to the expansive action of spring 50, thus relieving the pressure against packing material 26. This will enable air to enter the rear end of the cylinder through the stuffing box, to relieve the 70 vacuum tension which would otherwise oppose forward movement of the piston. The initial advancement prior to opening the outlet is relatively little; and when the pressure in front of the piston balances the force of 75 spring 50, the advancing of the piston will cease unless rotation of the handle continues. Assuming that such rotation is continued, the screw-shaft 21 will force itself to the rear, thus retracting valve 18 from seat 17. 80 Liquid will thereupon be emitted under pressure; and as the volume which remains in the cylinder decreases, the sleeve 52, shaft 21, rod 19, screw-sleeves and piston will move forward in unison in response to the expansive action of the spring. The valve 18 is thus caused continually to seek its seat 17 and will soon engage the seat unless further rotation is imparted to the handle to compensate for the forward travel of the piston. 90 A split ring 57 is arranged to keep the piston member 20 expanded against the cylinder. This keeps the piston tight and prevents rotation, thus insuring the desired screw action of the sleeves 38, 39 and 40. 95

The three sleeves, 38, 39 and 40, will advance in unison until the nut portion 38' of the inner sleeve is arrested by collar 29. Further advancement of the inner sleeve being thus prevented, the sleeves 39 and 40 will 100 continue to advance until nut portion 39' is arrested by flange 44. Thereafter, sleeve 40 will advance relatively to sleeves 38 and 39. Throughout the range of movement of the several screw-sleeves the spring 50 will 105 tend to keep the gland 25 against the collar 36; and whenever rotation of the handle is discontinued for a sufficient length of time to permit the spring to have its maximum expansion, the valve 18 will be forced against 110 its seat 17, the outlet being thus automatically sealed by the spring, regardless of the position of the piston, whenever the operation of the device is discontinued.

The operation of turning the handle backwardly at any time when the valve 18 is seated will cause a simple rotative movement of the valve on its seat, and thus remove or reduce any particle which might be lodged between the valve and seat. The word "simple" as used in the preceding sentence is intended to mean that the rotative movement is not accompanied by any other movement. This turning of the valve on its seat would necessarily occur in the course of adjusting 120 the parts to the position shown by Fig. 3, and could be done with the piston in any position.

I claim:

1. A device of the character described, comprising a cylinder and piston arranged 130

to coact, said cylinder having a discharge opening, and spring-actuated means arranged to propel said piston and automatically seal said discharge opening when 5 the piston has advanced a predetermined distance.

2. A device of the character described, comprising a cylinder and piston arranged to coact, said cylinder having a discharge 10 opening, spring-actuated means behind said piston arranged to propel the latter, and means arranged to be actuated by said propelling means to seal said discharge opening.

3. A device of the character described, 15 comprising a cylinder and piston arranged to coact, said cylinder having a discharge opening, a valve arranged to close said discharge opening, manually operative means arranged to coact with said piston to open 20 said valve, and a spring arranged to be flexed by valve-opening movement of said means and arranged to react to propel said piston and close said valve.

4. A device of the character described, 25 comprising a cylinder and piston arranged to coact, said cylinder having a valve seat and a discharge opening communicating with the latter, a valve arranged to coact with said valve seat to close said opening, 30 manually operative means arranged to coact with said piston to retract said valve from said seat, and a spring arranged to be flexed by valve-retracting movement of said means, said spring being arranged to react 35 upon said means to propel said piston and seat said valve.

5. A device of the character described, comprising a cylinder and piston arranged to coact, a manual operating member, and 40 telescopic members having coöperative screw-threads for transmitting motion from said operating member to propel said piston.

6. A device of the character described, 45 comprising a cylinder and piston arranged to coact, a manual operating member arranged behind said piston, telescopic members having coöperative screw-threads connecting said operating member and said 50 piston, said cylinder having a valve seat at its discharge end, a smooth cylindric valve rod extending through said piston, and arranged to coact with said valve seat, and a stuffing box carried by said piston and co- 55 acting with said rod, said rod being connected to said operating member to be retracted by the latter, and a spring arranged to coact with said cylinder and with said operating member to propel said piston and 60 said valve rod.

7. A device of the character described, comprising a container for liquid, said container having a discharge opening, means arranged in said container to discharge 65 liquid through said opening, and means ar-

ranged to be moved by the discharging operation of said discharging means at various stages of discharging to seal said opening.

8. A device of the character described, comprising a container for liquid, said container having a discharge opening, spring-actuated means arranged to discharge liquid through said opening, and means arranged to be moved by said spring-actuated means to seal said opening. 75

9. A device of the character described, comprising a container for liquid, said container having a discharge opening, spring-actuated means arranged to discharge liquid through said opening, and means carried by 80 said spring-actuated means to seal said opening.

10. A device of the character described, comprising a container for liquid, said container having a discharge opening, a valve 85 arranged to coact with said opening, spring-actuated means arranged to close said valve, and a piston carried by said spring-actuated means and arranged to discharge liquid through said opening while said valve is 90 closing.

11. A device of the character described, comprising a container for liquid, said container having a discharge opening, a valve arranged to coact with said opening, spring-actuated means arranged to close said valve, 95 a piston carried by said spring-actuated means and arranged to discharge liquid through said opening, and manually operative means arranged to cause relative adjustment of said piston and said spring-actuated means to prolong the discharging action. 100

12. A device of the character described, comprising a cylinder and piston arranged to coact, spring-actuated means arranged to propel said piston to discharge liquid, and manually operative means arranged to cause relative adjustment of said piston and said spring-actuated means to prolong the discharging action. 110

13. A device of the character described, comprising a cylinder and piston arranged to coact, a propelling spring, extensible means arranged to coact with said spring 115 and piston to transmit the force of said spring to said piston, and manually operative means arranged to extend said extensible means to prolong the propelling effect of said spring. 120

14. A device of the character described, comprising a cylinder and piston arranged to coact, a propelling spring, coöperative screw members arranged to be moved axially by said spring to propel said piston, 125 and manually operative means arranged to cause relative rotation of said screw members to prolong the propelling effect of said spring.

15. A device of the character described, 130

comprising a cylinder and piston arranged to coact, a propelling spring, co-operative screw members arranged to be moved axially by said spring to propel said piston, manually operative means arranged to cause relative rotation of said screw members to prolong the propelling effect of said spring, said cylinder having a discharge opening, and means carried by said manually operative means and arranged to be moved by said propelling spring to seal said discharge opening.

16. A device of the character described, comprising a cylinder and piston arranged to coact, piston-operating means arranged behind the piston, sealing means arranged to coact with said operating means to seal the cylinder behind the piston, said cylinder having a discharge opening in front of the piston, and sealing means arranged to seal said discharge opening, said piston-operating means having provisions for exerting stress upon the two said sealing means in opposite directions to seal the cylinder.

25 17. A device of the character described, comprising a cylinder and piston arranged to coact, piston-operating means arranged behind the piston, sealing means arranged to coact with said operating means to seal the cylinder behind the piston, said cylinder having a discharge opening in front of the piston, and sealing means arranged to seal said discharge opening, said two sealing means being arranged to coact with each other to seal the cylinder simultaneously behind and in front of the piston, both said sealing means being arranged to be moved to unseal the cylinder by piston-operating movement of said operating means.

40 18. A device of the character described, comprising a cylinder and piston arranged to coact, piston-operating means arranged behind the piston, sealing means arranged to coact with said operating means to seal the cylinder behind the piston, said cylinder having a discharge opening in front of the piston, and sealing means arranged to seal said discharge opening, said two sealing means being arranged to coact with each other to seal the cylinder simultaneously behind and in front of the piston, one of said sealing means being arranged to be moved to unseal the cylinder by piston-operating movement of said operating means.

55 19. A device of the character described, comprising a cylinder and piston arranged to coact, piston-operating means including a screw shaft arranged behind said piston, a stuffing box arranged to coact with said screw shaft to seal the cylinder behind the piston, said cylinder having a discharge opening in front of the piston, and sealing means arranged to seal said discharge opening, said operating means being arranged to coact with the gland of said stuffing box and

with said sealing means to seal the cylinder simultaneously behind and in front of the piston.

20. A device of the character described, comprising a cylinder and piston arranged to coact, piston-operating means behind the piston, means arranged to coact with said operating means to seal the cylinder behind the piston, said cylinder having a discharge opening in front of the piston, and sealing means arranged to seal said discharge opening, both said sealing means being arranged to have sealing pressure imparted to them by said operating means when the latter is adjusted to retract the piston.

15 21. A device of the character described, comprising a cylinder and piston arranged to coact, a propelling spring, telescopic screw members arranged to transmit the force of said spring to propel said piston, and means arranged to be operated manually to cause relative rotation of said screw members to flex said spring.

22. In a fire extinguisher, the combination of a casing having a discharge nozzle, a piston shiftably mounted in said casing for forcing the contents out through said nozzle, mechanism for shifting said piston, a valve normally urged to close said nozzle, and means actuated by said mechanism for retracting said valve when said piston has been shifted to increase the pressure on the contents in said casing above a certain predetermined amount.

25 23. The combination of a casing having a discharge orifice, a valve for said orifice, means normally urging said valve to a closed position, a member shiftably mounted in said casing and connected to said valve, and mechanism for creating pressure in said casing to coact with said member to open said valve and then discharge the contents of said casing.

40 24. A device of the character described, including a container, adapted to hold a liquid and formed with an outlet, a piston movable in the container, a stem mounted to turn in the container and adapted to actuate the piston in either direction, the stem being movable longitudinally in the container, and there being a valve movable with the longitudinal movement of the stem to open or close the said outlet; a spring normally tending to move the stem to a position to seat said valve and of sufficient strength to effect such movement, means to turn the stem, means to press the spring during movement of the stem to unseat said valve, and a stop to limit the rearward movement of the stem after unseating the valve, the continued turning of the stem serving to actuate the piston.

55 25. In a fire extinguisher, the combination of a casing having a discharge nozzle, a piston shiftably mounted in said casing for

forcing the contents out through said nozzle, a threaded member rotatably mounted in said casing and engaging said piston, mechanism extending to the outside of said casing 5 and connected to rotate said member for shifting said piston; a valve normally urged to close said nozzle, and means actuated by the movement of said member in said casing for retracting said valve when said piston 10 has been shifted to increase the pressure on the contents in said casing beyond a certain predetermined amount.

26. In a fire extinguisher, the combination of a casing adapted to contain a liquid, an outlet from said casing at one end thereof, a threaded mechanism having means at one 15 end thereof to normally close said outlet, a plunger in said cylinder threadedly engaging said mechanism, means located exteriorly of said casing and connected to said mechanism for rotating the latter, and means at the end of said casing opposite said outlet to engage said plunger and thereby force 20 said outlet-closing means into closing position.

27. In a fire extinguisher, the combination of a casing adapted to contain a liquid, an outlet from said casing at one end thereof, a threaded mechanism having means at one 25 end thereof to normally close said outlet, a

plunger in said cylinder threadedly engaging said mechanism, means located exteriorly of said casing and connected to said mechanism for rotating the latter, and resilient means at the end of said casing opposite 35 said outlet to engage said plunger and thereby force said outlet-closing means into closing position.

28. The combination in a hand operated fire extinguisher, of a fluid containing tube, 40 a piston reciprocable therein, a plurality of concentric inter-engaging screw members, one of said members being secured to the piston, and means for rotating one of the other members.

29. The combination in a hand operated fire extinguisher, of a fluid containing tube, 45 a piston reciprocable therein, a plurality of telescoping inter-engaging screw members, one of said members being secured to the piston, means for rotating one of the other members, and means for preventing rotation 50 of the piston relative to the tube.

In testimony whereof I have affixed my signature, in presence of two witnesses.

DANA ESTES.
